UNITED STATES PATENT OFFICE.

BENJAMIN CRAVEN, OF BRADFORD, ENGLAND.

WOOL-COMBING MACHINE.

Application filed April 20, 1927, Serial No. 185,189, and in Great Britain June 23, 1926.

This invention relates to improvements connected with wool combing machines, and refers to the feed motion for "Noble" combs.

The usual feed motion consists of a trip arm operated by inclines or cams from the moving part of the comb, which arm carries a pawl to operate a toothed wheel, which in turn moves the rollers, the wool being drawn to the comb by means of boxes and gear connected therewith. I find that this arrangement is not entirely satisfactory, due to the weight of material causing a tendency for a movement opposite in direction to the feed movement.

My invention is in the nature of a rack suitably operated to move a pinion which in turn operates a worm which engages and operates a worm wheel in connection with the rollers. This gives a positive feed, not subject to back lash, and obviates the use of the usual inclines.

The teeth on the rack may be made variable to suit the desired feed, and the teeth of the pinion will be constant, but in an alternative form the teeth of the pinion may be variable as to teeth and the rack be constant.

Referring to the drawings which form part of this specification:—

Fig. 1 represents a sectional elevation of a comb with my invention applied thereto.

Fig. 2 represents a plan.

Fig. 3 represents an elevation of an alternative form of construction.

Fig. 4 represents a plan of the mechanism shown in Fig. 3.

Figs. 5 and 6 represent details of a modified form of rack hereinafter referred to.

To carry my invention into effect and with reference to the drawings which illustrate a convenient method of construction and modifications thereof, I wish it to be understood that I may further vary the details, so long as I operate the rollers F by means of a rack and pinion device actuating a worm wheel motion.

The existing castings and brackets or hangers of a "Noble" comb will be used where possible, filing, boring, or adding to same as may be found necessary.

In the form illustrated in Figs. 1 and 2, from a suitable and preferably adjustable bracket A mounted in connection with the comb base B I carry a rack in this case constituting a member R carrying pegs R' readily detachable in order that the length of

rack may be varied to alter the feed. The member R may be moved in or out of the bracket A and the bracket A may be raised or lowered to suit varying requirements.

The rack will engage a suitable wheel such as star wheel S carried on a shaft S' which in turn is carried by a bracket H' attached to one of the usual hangers H. The shaft S' terminates in or carries in a suitable position a worm S² which engages a worm wheel S³ suitably carried from a bracket or bearing attached to the hanger H or bracket H'. This worm wheel will have a preferably square boss S⁴ which will be engageable by a squared end F' of the rollers F, one gear serving two rollers and giving to the same a positive feed motion with freedom from back lash.

As before mentioned the teeth of the rack may be varied as to number and the rack be variable as to length but alternatively I may use the wheel S as a change wheel and alter the number and pitch of teeth therein.

Referring to Figs. 3 and 4, in this form the rack mechanism comprises a spring box R² carried by the bracket A and springs R³ will contact with a rack plate R⁴ which in turn will carry a rack R⁵ made in one or more portions. This rack will operate a wheel in the nature of a spin wheel S^x carried on the shaft S' the other portions being as heretofore described.

Figs. 5 and 6 show a further modification of a rack device carried by the bracket A and comprising a box like device R⁶ carried by fixable pinions R⁷. The box like device may have any suitable number of equal or substantially equal sides, each side or face carrying a rack of different length to enable a change to be quickly made, a set screw R⁸ being provided to fix the desired rack in position.

It will be seen that in addition to obtaining a constant and positive feed, such feed or traverse may be quickly and easily changed, either by, in some forms, changing the star and spur wheel and leaving the rack constant, or by changing the rack, and while I prefer one motion to operate two rollers F, in some cases each roller may be operated independently. Where two rollers are operated at once two racks per comb will be sufficient.

What I claim is:—

1. In a feed motion for the feed rollers of "Noble" combs, the combination of rotatable

feed rollers, a worm and worm wheel adapted to drive said rollers, and a rack and pinion mechanism for driving said worm.

2. A feed motion for the feed rollers of 5 "Noble" combs, comprising in combination, a rotatable frame, a stationary rack, a wheel carried by said frame and adapted to contact with and be rotated by said rack as the frame rotates, feed rollers mounted for rotation in said frame, and worm gearing between said wheel and the arbors of said feed rollers for imparting a positive feed motion thereto.

3. A feed motion for the feed rollers of 10 "Noble" combs, comprising in combination, a rotatable frame, a normally stationary, adjustable rack, a wheel carried by said frame and adapted to contact with and be driven by the rack as the frame rotates, feed rollers

mounted for rotation in said frame, a worm 20 driven by said wheel, and a worm wheel in engagement therewith and engaging the arbors of said feed rollers for imparting a positive feed motion thereto.

4. A feed motion for the feed rollers of 25 "Noble" combs, comprising in combination, a rotatable frame, a stationary rack, a removable wheel carried by said frame and adapted to contact with and be driven by the rack as the frame rotates, feed rollers 30 mounted for rotation in said frame, and worm gearing between said wheel and the arbors of said feed rollers for imparting a positive feed motion thereto.

In testimony whereof I have signed my 35 name to this specification.

BENJAMIN CRAVEN.
